(57) CLAIM

The ornamental design for a light fixture, as shown and described.

DESCRIPTION

FIG. 1 is a perspective view of a light fixture showing my new design;

FIG. 2 is a front view thereof, the right side, left side, and back views being identical thereto;

FIG. 3 is a side view thereof rotated about its central vertical axis approximately 45 degrees from the position shown in FIG. 2;

FIG. 4 is a top view thereof; and,

FIG. 5 is a bottom view thereof.

The broken lines are shown in the views for illustrative purposes only and form no part of the claimed design.
